COIN CONTROLLED LIQUID DISPENSER

Charles D. Wood, Texas City, Tex.

Application May 10, 1939, Serial No. 272,911

1 Claim. (Cl. 221—101)

This invention appertains to new and useful improvements in liquid dispensers and more particularly to a liquid dispenser such as is especially adapted for dispensing gasoline at service stations wherein coin controlled means is employed.

The principal object of the present invention is to provide a coin controlled gasoline or other fuel or liquid dispensing machine which can be operated without proprietorship attendance.

Another important object of the invention is to provide a simple and inexpensive gasoline pump which is fully automatic in operation and adapted to be operated by coin controlled mechanism.

These and other objects and advantages of the invention will become apparent to the reader of the following specification.

In the drawings,

Figure 1 represents a front elevational view of the dispenser.

Figure 2 is a diagrammatic view disclosing the electrical connections between the elements of the mechanism.

Figure 3 is a fragmentary detailed sectional view of the coin chute and coin non-return means taken substantially on the line 4—4 of Figure 1.

Figure 4 is a fragmentary detailed sectional view disclosing the coin mover button means.

Figure 5 is a fragmentary detailed sectional view taken substantially on a line 5—5 of Figure 2.

Figure 6 is a sectional view taken substantially on a line 6—6 of Figure 3.

Figure 7 is a sectional view taken substantially on a line 7—7 of Figure 2.

Figure 8 is a sectional view on the line 8—8 of Figure 2.

Referring to the drawings wherein like numerals designate like parts, it can be seen that if desired the gasoline pump can be in the form of a lighthouse such as is generally referred to by numeral 5. Of course, the case construction can be of any shape or design desired, but will have the coin chute 6 opening through the front wall thereof and at this front wall will be the window 7 through which the dial 8 is visible and the discharge nozzle will connect to the turbine outlet 9.

As shown in Figure 3, the coin chute 6 will curve downwardly and terminate over the neck 10 of the coin mover case 11 in which the rotor 12 is operative and suitably keyed or secured to the shaft 13. This rotor 12 has the coin receiving pocket 14 therein for receiving coins 15 which drop from the slot 6 and incidentally pass be-

tween the fingers 16 of the coin non-return unit which is generally referred to by numeral 17 (see Fig. 6). This coin non-return means consists of ears 18 projecting laterally from the lower portion of the chute 6 and on these ears 18 are rockably supported bell crank structures each consisting of a finger 16 and a shank 17, with the shank 17 carrying weight members 19, these weight members serving to hold the terminals of the fingers 16 in abutting relation as shown in Figure 6. However, these weight members are only heavy enough to barely keep the fingers 16 together so that a coin will readily spread the same apart as it drops into the underlying pocket 14 of the rotor 12. However, if a string or other line is attached to the coin it cannot be pulled back upwardly beyond the non-return unit 17.

The coin mover case 11 has the discharge spout 20 at its bottom and this is disposed over the opening 21 in the coin collection receptacle 22.

Spring pressed plungers 23—23 are provided in opposite side walls of the coin mover case 11. These plungers project through barrels 24 which have binding posts 25 and these plungers are electrically connected with contacts 26—26 which are adapted to be bridged by a coin carried in a pocket 14 of the rotor 12 as it registers with the contacts 26.

Numeral 27 represents the resistance meter which has the branch wire 28 from the conductor 29 connected thereto, this conductor 29 extending from one binding post 25 to one side of the battery 30. A conductor 31 extends from the other binding post 25 to the other side of the battery 30 and from this conductor 31 a branch conductor 32 extends to the switch 27. Numeral 33 represents a conventional magnetic switch, one side of which is connected to the stationary contact of the rotary switch generally referred to by numeral 34 while the contact arm 35 of the switch 34 is connected by the conductor 36 to one side of the electric motor 37. The other side of the electric motor 37 is connected by the conductor 38 to one side of the line switch 39 which has the line 40 connected thereto. The other side of the switch 39 has the jumper 41 to a conventional pressure control switch 42 which has a tube 43 extending therefrom to the pump pipe 44, the latter extending from the pump 45 to the turbine 46, the turbine having the outlet 9 and being internally constructed as substantially shown in Figure 7. This turbine of course rotates the shaft 13. Numeral 47 denotes the return line from the pump pipe 44 and this has the relief valve 48 therein. Numeral 49 denotes the

inlet for the pump 45 which is preferably of the rotary gear type.

As shown in Figure 8, the rotary switch 34 consists of the body 50 of insulation on which is the split conductor ring 51 having the gap 52 between which the arm 53 will normally set, which can wipe the contact strip 51 to maintain the line to the motor 37 closed when the apparatus is in operation.

For setting the gage 8, the ratchet means shown in Figure 4 is employed. This consists of the bracket 55 through the foot 56 of which is slidably disposed the rod 57, this rod also extending through the front of the case structure 5 having a finger engageable button 58 between which and the case 5 a coiled compression spring 59 is interposed. The inner end of the rod 57 carries the pawl 60 which is slidably disposed through the lug 61 which projects laterally from the case 62 of the dial 8. Numeral 63 represents a coiled spring for projecting the pawl 60 toward the ratchet wheel 64. This ratchet wheel is suitably secured to the shaft 13. This machine is operated by inserting a coin or check into the chute 6. The coin passes downwardly between the gates 16 which, of course, preclude the possibility of the coin being retrieved by a string or other attached member. The coin lodges in a pocket 14 of the rotor 12 and by rotating the shaft 13 by the pawl 60 and ratchet 64, the coin is brought into position bridging the contacts 26. The resistance of the metal in the coin is registered on a galvanometer which has two additional contacts allowing the same to serve as a single pole switch. This switch controls a magnetic switch 33 which, in turn, controls the line current to the rotary switch 34, which, in turn, controls the duration of the current supply to

the motor 37. The purpose of the rotary switch 34 is to govern the amount of the fuel dispensed. Obviously, the rotor 50 (see Figure 8) can be seen from time to time to permit replacement of rotors 5 having different lengths of contacts 51. The motion for the rotary switch 34, the dial 8, and the coin holder 12 is furnished by the turbine 46 which, in turn, is operated by the fluid moving to the outlet 9 under pressure from the pump 45, the pump being driven by the motor 37.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A liquid dispensing machine comprising a liquid source, a pump, an electric motor in driving connection with the pump, said liquid source being connected to the pump, and an outlet conduit from the pump, a turbine to which the conduit is connected, a dispensing outlet for the turbine, a shaft driven by the turbine, a current supply, a duration switch on the shaft interposed between the current supply and the motor, and manual means for setting the shaft, said manual means consisting of a ratchet wheel on the shaft, a bracket, a slide member slidably supported by the bracket, a pawl having a shank slidably disposed through the slide member, spring means for normally engaging the pawl with the ratchet wheel, a manually engageable head at the outer end of the slide member and spring means for holding the slide member in an outwardly extended position with respect to the pawl.

CHARLES D. WOOD.
